(57) **CLAIM**

The ornamental design for a display screen with graphical user interface, as shown and described.

DESCRIPTION

FIG. 1 is a front view of a display screen with graphical user interface showing my new design;

FIG. 2 is a front view of a second embodiment thereof; and, FIG. 3 is an additional view of the design of FIG. 1, shown with alternative unclaimed subject matter.

The broken line showing of the display screen and portions of the graphical user interface illustrate the environment of the claimed design and form no part thereof.
